UNITED STATES PATENT OFFICE.

JAMES BRYAN, OF LYNN, MASSACHUSETTS.

GAS-ENGINE.

SPECIFICATION forming part of Letters Patent No. 542,972, dated July 16, 1895.
Application filed February 10, 1894. Serial No. 499,728. (No model.)

To all whom it may concern:

Be it known that I, JAMES BRYAN, a citizen of Great Britain, and a resident of Lynn, in the county of Essex and Commonwealth of Massachusetts, have invented a new and useful Improvement in Gas-Engines, of which the following is a specification.

My invention relates to improvements in engines of the above class; and it consists of improvements in the arrangement of induction and exhaust ports and valves controlling the same and of the devices and combination of devices hereinafter more specifically set forth and claimed.

15 The object of my invention is to increase the effectiveness and steadiness of the operation of this class of engines.

My invention is illustrated by the drawings herewith submitted, in which—

20 Figure I is a sectional view taken on line X X, Fig. II, showing, however, in side elevation mechanism for regulating the quantities of air and gas utilized to form the charge. Fig. II is a view of an engine embodying a 25 form of my invention, taken partially in section and plan view. Fig. III is a side view of a portion of my regulating device. Fig. IV is an enlarged sectional view of a device for pumping gas. Fig. V is an enlarged sectional 30 view of a portion of the piston, showing the arrangement of air-valves in same. Fig. VI is an end view of same. Fig. VII is an enlarged view, partially in section, showing form and arrangement of valves for admitting gas and exhausting air and products of previous firing. Fig. VIII is an enlarged sectional view of gas-pressure regulator. Figs. IX and X are detailed views showing mechanism for operating gas-pump by hand in 35 40 starting the engine. Figs. XI and XII are detailed views showing device for controlling action of firing-valves when the engine is being started. Figs. XIII and XIV are enlarged end views of cams controlling air and 45 gas valves, respectively.

Similar letters and figures of reference refer to similar parts throughout the several views.

Reference being had to the drawings, A 50 represents the frame in which the working parts of the engine are mounted. It will be noted that in the drawings portions of the

frame A have been omitted to avoid confusion; but the same can readily be supplied by one skilled in the art and form no part of my invention.

I will now describe a preferred form of my device for supplying, compressing, and firing the charge at each end of the cylinder at every revolution; but before doing so I wish 60 to be understood as not intending to limit my invention to such form or arrangement, as it is evident that many variations therein may be made without affecting the essential nature of my invention.

65 Mounted upon the frame A is a cylinder B, composed of three parts b b and b'. The parts b b may be said to form a working-cylinder and the part b' the air-cylinder. Working in the cylinder B is a piston C, which consists of three parts c c and c' and the rigid connection 1 uniting the same. The parts c c form the working-piston and the part c' the air-piston. The parts c c work in the parts b b, respectively, and the part c' in the part b'. 70 In each of the parts c c of the working-piston is placed a valve 2, arranged to open and close a port leading through the part c', opening 75 outwardly and closing inwardly.

A convenient form and arrangement of the 80 valve 2 (see Fig. V) consists of a common-form piston-valve, working against a valve-seat near the outer end of the piston, the valve working in a collar 6 of less external diameter than the piston. In the collar 6 are 85 side ports 7 7, which communicate with the cylinder. The stem 3 of the valve 2 extends into a close casing 4, supported by the lugs 5 5, &c., secured to the piston C. When the valve 2 is raised the air passes round the casing 4 out through the ports 7 7. When the valve 2 is raised a vacuum is created in the close casing 4 by the outward motion of valve-stem 3, and the valve 2 will be closed by atmospheric pressure when the pressure which 90 tends to open it is sufficiently reduced.

In each of the parts b b of the working-cylinder is a port 8, which connects the same with the atmosphere. The ports 8 8 are closed by the sliding valves 60 60 carried by the piston C.

100 Communicating through the ports 10 10 with the air-cylinder b' is a valve-chamber 9, which is connected with the atmosphere by the port

11, controlled by the elastic or spring-controlled valve 12. The adjustment of valve 12 is such that when the air in the air-cylinder b' is expanded below an atmosphere, as hereininafter described, the valve 12 rises and admits air until the pressure in cylinder b' rises to an atmosphere.

At each end of the working cylinder is a firing-chamber D, which may be of any suitable form and in which the charge is ignited. In each of the chambers D D is an exhaust-valve 19, which controls a port or ports 13, connecting the said chamber with the exhaust 23. The valve 19 is controlled by the cam 28 and may be conveniently constructed in form of common piston-valve, the stem 21 of which extends through a suitable bearing below the chamber D and carries a roll 22, which rests upon the cam 28, being held in contact therewith during revolution of cam 28 by gravity or by a suitably-arranged spring.

Gas is admitted to each of the chambers D D through the perforated pipes 14 14 14, which communicate with chamber 15, which the gas enters from the supply-pipe 24 through suitable ports 16, controlled by the valve 20, the action of which is controlled by cam 27. The form and arrangement of valve 20 are substantially similar to that of valve 19, the stem 18, however, being conveniently provided with suitable packing to prevent escape of gas about same. The chambers D D are further each provided with a firing device, a convenient form of which consists of a tube 70, which is heated by a Bunsen burner 71 sufficiently to ignite the mixture entering the same. The mixture is admitted to the tube 70 through a port 99 communicating with the chamber D. The admission of the mixture to igniting-tube 70 is controlled by a valve 72 operated by an eccentric on shaft 40. The shaft 40 is suitably mounted in bearing-frame A and may be conveniently operated by connecting-gears from the main shaft.

45 The valve 72 (not shown in detail in the drawings) is conveniently constructed in form of a perforated sliding valve, which, when the perforation therein corresponds with port 99, admits mixture to tube 70.

50 The cams 27 27 and 28 28 rotate with shaft 25, which is suitably mounted in frame A and driven from shaft 40 by connecting-rod and system of gears or other convenient device.

55 Since gas enters chamber D after compression has commenced therein, as hereinafter described, I find it convenient to provide a gas-pump H, which maintains the necessary pressure in the supply-pipe 24.

As shown in the drawings, the pump H consists of a common form of double-action pump, which, as I claim no invention thereon, I regard as unnecessary to describe in detail. Gas is admitted to pump H from convenient source of supply through the ports 46 46 and forced into the pipe 24. (See Fig. IV). To regulate the pressure in the pipe 24 I have provided a regulating-valve 50, which works

in a chamber 51, to which gas is admitted by a port through the valve-seat.

The valve 50 may be a gravity, as shown, 70 or spring-controlled, or elastic valve, and is so adjusted that it rises and admits gas to chamber 51 when the pressure in pipe 24 rises above the desired point. Gas escaping into chamber 51 is reconducted to the pump 75 H by a pipe 52.

The pump H may be conveniently operated by an eccentric (not shown) upon the main shaft 93 by suitable pivoted connecting-rod 53, connecting same with valve-rod 78. 80

For convenience in starting the engine the connecting-rod 53 is arranged to be lifted out of connection with valve-rod 78 and a hand-lever 54 provided, which may be attached to rod 78 and pump H operated thereby. (See 85 Figs. IX and X.)

In Figs. XI and XII I have shown a convenient form of device for preventing premature firing. When the engine is being started, the end of valve-rod 72 is forked and embraces the connecting-rod 98, which connects it with its eccentric on shaft 40 and is coupled thereto by an eccentric-pin 87, by turning which the valve-rod 72 is brought toward or moved away from the eccentric, and the 95 length of stroke remaining the same the time when the perforation reaches port 99 will vary, occurring earlier or later in the stroke, and the time of admission of mixture to firing-tube will correspondingly vary, and, consequently, the time of firing.

In order that description of parts herein-after contained may be more clearly understood, I will now describe the correlative operation of parts heretofore described.

As shown in Fig. I, the piston C is substantially at the limit of its stroke. Let us presume that it has just started upon its return stroke under impulse of firing of charge in chamber D. As the air-piston c' moves along the air-cylinder b' it expands the air back of it and compresses the air in front of it. This operation draws in air through the port 8 (behind the piston c') and opens the valve 2, (in front of the piston c'), sending a current of 115 air through cylinder b, which carries off products of previous combustion through the ports 13, while valve 19 is held open by the cam 28 and cools the cylinder b. The valve 19 then closes, and sufficient air is retained in cylinder B to form next charge. The amount of such supply is determined by time when the valve 19 closes, and hence controlled by cam 28. The above operations are performed before the piston c' has opened the 125 first port 10. As the piston c' passes over the first port 10, the sliding valve 60 closes the port 8 (back of piston c'), and the compressed air in front of the piston c' passes through the ports 10 10 to the cylinder back of the 130 piston c', where the air is being expanded. This releases pressure on valve 2, which closes, and compression of air in chamber D and cylinder b by piston c commences. The valve

125

20, which controls ports 16, by which gas enters chamber D, is arranged to be opened by the cam 27 upon the closing of the valve 19, so that the supply of gas to be utilized for the charge is mixed with the air during compression. The perforated pipes 14 14 14 act to scatter the gas entering chamber D, so that it more readily mixes with the air. The valve 20 is arranged to close before the piston C 10 has reached the limit of its stroke. As the air-piston c' passes the last port 10 the sliding valve 60 opens the port 8, (in front of piston c'), allowing the air in front of piston c' and behind piston c to pass out, and at the 15 same time, the air in the cylinder b' back of piston c' being expanded below an atmosphere, the valve 12 opens, admitting air until pressure in air-cylinder rises to an atmosphere. The compression of air and gas by 20 piston c, commenced as heretofore described, is continued until piston C has substantially reached the limit of its stroke and the firing-valve 72 opens to admit the mixture to firing-tube and fires the charge supplied and 25 compressed in chamber D, as described. The above operations are substantially repeated upon the return stroke by mechanism upon the other end of the cylinder.

It will be noted that in its operation, as just 30 described, the air from before piston c' cools the cylinder b and supplies air for the next charge, at the same time accumulating in the cylinder B a sufficient quantity of air to be used upon return stroke.

35 The cams 28 28 are formed and timed to open the valves 19 19 alternately when the piston C reaches substantially the limit of its stroke and to allow them to close at sufficient time before the piston c' passes port 10 to retain the desired amount of air in cylinder b and chamber D for the charge. The cams 27 27 are so formed and timed that they open 40 the valves 20 20 alternately upon the closing of the valves 19 19 and allow the same to close 45 before the piston C reaches the limit of its stroke.

I find that the most effective mixture of gas and air is composed of about eight parts of air to one of gas, and the cams 27 and 28 50 are formed and size of ports 13 and 16 arranged with reference to each other to give this result, which, of course, may be varied by varying the form of cams or size of ports. This brings me to a description of my device 55 for varying the quantity of charge without varying ratio of quantities of air and gas contained therein.

It will be noted from the foregoing description that the time of opening valve 19 and 60 closing valve 20 cannot be conveniently varied. Therefore to regulate the quantity of charge I vary the time of closing valve 19 and opening valve 20, and by making such variations proportional do not affect the ratio of 65 quantities of air and gas.

I find a convenient method of securing above result to be the following: The cams

27 27 are constructed of sufficient width for purposes hereinafter set forth, and the end sections varied substantially as shown in Fig. XIV, and such variations distributed proportionally along the cam. The portion of the face a' of the cam 27 along which the variation occurs is the opening portion—that is, the portion of the face that raises valve 20— 75 and the portion e' of the face of cam 27 along which the sections remain unchanged is the closing portion. In the cam 28 the end sections are varied, as shown in Fig. XIII, and such variation distributed proportionately 80 along the face of the cam; but in cam 28 the variations occur along the portion e of the face, which is the portion which allows valve 19 to close, while the opening-face a does not vary. (See Fig. XIII.) The cams 27 and 28 are 85 mounted upon or made integral with the sleeve 26 and so arranged thereon that when the sleeve 26 is moved along the shaft 25 in one direction the valve 19 closes and valve 20 opens earlier and when moved in the other direction the valve 19 closes and valve 20 opens later. The sleeves 26 26 are splined to shaft 25 and rotate therewith and are free to slide thereon. They are connected by the rigid connecting-rods 30 30. To a suitable collar secured to sleeve 26 is pivoted one end of a lever 31, intermediately pivoted to frame A, and pivoted at or near the other end to a connecting-rod 32, pivotally connected with the threaded shaft 33, which engages with 105 the threaded sleeve 34, carried by shaft 35, mounted in suitable bearings in frame A. The shaft 35 carries a friction-disk 45. Also mounted in suitable bearings in frame A is a vertical shaft 36, which may be conveniently 105 driven by a pulley 38, geared thereto, and driven by belt from the pulley 41 on shaft 40. The shaft 36 carries a gravity or centrifugal governor 37. On the shaft 36 is a sleeve 42, splined thereto, rotating therewith, and free 110 to slide thereon. The sleeve 42 carries the friction-disks 43 and 44 and is suitably connected with the governor 37, so as to be raised or lowered by the action of same.

The operation of this device is as follows: 115 When the speed of engine rises above a limit determined by adjustment of governor the sleeve 42 is raised and disk 44 brought in contact with disk 45, causing rotation of shaft 35 and moving threaded shaft 33 along sleeve 120 34, and, by connecting-rod 32 and lever 31, moving sleeves 26 26 along shaft 25, thereby causing valves 19 19 to close later and valves 20 20 to open later, thereby reducing proportionately the amounts of air and gas in mixture, and hence the degree of compression produced by piston C and the amount of energy developed by the firing, and conversely when the speed of the engine falls below the desired speed. To the piston C are secured 125 130 the rods 90 90, which extend through the cylinder-head and are connected with the cranks 92 on the shaft 93 by the pivoted connecting-rods 91 91. By such or other convenient de-

vice the sliding motion of piston C is converted into rotary motion of main shaft 93. The main shaft 93 may be provided with a fly-wheel 94, which acts to steady the working 5 of the engine. For convenience in lubricating cylinder I have provided the oil-holes 95 95.

It will be noted that by above arrangement 10 the piston travels across the cylinder and back to produce a revolution of shaft 93, and that during this time a firing occurs in each 15 of the chambers D D.

It will be noted that the piston C compresses the charge during a portion only of 15 its stroke—to wit, after the air-piston c' has passed over the port 10, as hereinbefore described, and that the heated products of firing are allowed to expand through substantially the whole stroke, the exhaust 19 not 20 opening until the piston has reached substantially the limits of its stroke. By this means I am enabled to utilize more fully the energy developed by ignition of the charge than has 25 been heretofore done in other forms of gas engines.

It will be also noted that before recharging I pass a current of air through the cylinder b. By this means I cool said cylinder and keep 30 it within lubricating limits, dispensing wholly or in part with water-jacket and other forms of cooling device heretofore used for that purpose.

I further wish to say that with slight modifications in details my invention may be 35 adapted to engines using vaporized liquid fuels and to other forms of internal-combustion engines.

The operation of my invention has already 40 been sufficiently described, and

I therefore claim as novel, and desire to secure by Letters Patent, in a gas or internal-combustion engine—

1. The combination of a working and air pumping cylinder arranged in line, connected 45 working and air pumping pistons, a port for the admission of air from the air pumping cylinder to the working cylinder, a valve arranged to close said port during a portion of the stroke of the air pumping piston, and 50 means for connecting the compression side of the air pumping piston, back of the working piston, with the atmosphere as the pistons approach the limit of their compression stroke, substantially as described.

2. The combination of two working cylinders and an interposed air pumping cylinder arranged in line, rigidly connected air pumping and working pistons, suitably controlled ports connecting the working and air pumping cylinders, connected ports in the air pumping cylinder for passing air from the compression to the suction side of the air pumping piston, and suitably controlled air induction and exhaust ports in the working cylinder adjacent to the air pumping cylinder, 60 substantially as described.

3. The combination of two working cylinders and an interposed air pumping cylinder arranged in line, connected air pumping and working pistons, suitably controlled ports 70 connecting the air pumping and working cylinders, means for exhausting from the compression to the suction side of the air pumping piston at or near the center of its stroke, and means for exhausting from the compression side of the air pumping piston to the atmosphere at or near the limits of its stroke 75 substantially as described.

4. The combination of two working cylinders and an interposed air pumping cylinder 80 arranged in line, connected air pumping and working pistons, suitably controlled ports connecting the air pumping and working cylinders and a series of air induction ports located at or near the center and opposite ends 85 of the air pumping cylinder, substantially as described.

5. The combination of two working cylinders and an interposed air pumping cylinder arranged in line, connected air pumping and 90 working pistons, suitably controlled ports connecting the air pumping and working cylinders, air induction and exhaust ports adjacent to the opposite ends of the air pumping 95 cylinder, connected ports in the air pumping cylinder on each side of and adjacent to its center, and a suitably controlled air induction 100 port communicating with the connected ports in the air pumping cylinder, all substantially as described.

In testimony whereof I have hereunto set my hand, in the presence of two subscribing witnesses, this 22d day of January, A. D. 1894.

JAMES BRYAN.
